UNITED STATES PATENT OFFICE.

HARRY E. GUYER, OF PHILADELPHIA, PENNSYLVANIA.

DESIGN FOR AN EYEGLASS-CASE.

SPECIFICATION forming part of Design No. 30,934, dated June 6, 1899.

Application filed May 12, 1899. Serial No. 716,588. Term of patent 7 years.

To all whom it may concern:

Be it known that I, HARRY E. GUYER, a citizen of the United States, residing in the city and county of Philadelphia, State of Pennsylvania, have invented and produced a new and original Design for an Eyeglass-Case, of which the following is a specification, reference being had to the accompanying drawings, forming part thereof.

- The leading feature of my design for an eyeglass-case is a body of triangular form in cross-section and an angular cover.

Figure 1 represents a perspective view of an eyeglass-case embodying my design. Fig. 2 represents a section on the line $x x$, Fig. 1. In the drawings, A designates the body of

the case, the same consisting of the front B, the back C, the sides D, and cover E. The front is flaring, the back is flat, and the sides are flaring, producing a triangular shape of 20 the body, as more particularly shown in Fig. 2. The cover is of angular form, composed of the limbs F and G.

Having thus described my invention, what I claim as new, and desire to secure by Letters 25 Patent, is—

The design for an eyeglass-case substantially as shown and described.

HARRY E. GUYER.
